UNITED STATES PATENT OFFICE.

STEPHEN F. SHERMAN, OF NEWARK, NEW YORK.

FOLDING BOX.

SPECIFICATION forming part of Letters Patent No. 516,124, dated March 6, 1894.

Application filed November 28, 1893. Serial No. 492,219. (No model.)

To all whom it may concern.

Be it known that I, STEPHEN F. SHERMAN, a citizen of the United States of America, residing at Newark, Wayne county, New York, 5 have invented certain new and useful Improvements in Folding Boxes, of which the following is a specification.

My invention consists in certain novel features pertaining to folding-boxes and blanks 10 therefor, which may be cut at single impressions from suitable sheet material. Cuts and creases divide the blank into suitable sections for the four sides and bottom in the customary way. To certain of these fundamental 15 sections, I have added extensions which may be folded over to form binding strips which hold the sides together; and in addition, I have added sections which form a suitable cover or covers, and flaps by which 20 they are supported. In so doing, the various sections are disposed so that the blank is substantially rectangular and there is little waste.

In certain forms of my invention I also add 25 sections at right angles to the binding strips which are formed into handles. These sections, since they are attached to the binding strips which fold over, project interiorly to the blank, occasioning no waste and enabling the 30 rectangular outline of the blank to be pre- served. These several features independently and in co-operation, as hereinafter described and claimed, comprise my invention. Corner sections and suitable tongues and slits 35 which serve to stiffen and hold the sections together are also advantageous features of my boxes.

It will be seen from the following description 40 that these boxes are of such construction that they are securely held together without glue, tacks or other similar means of fastening.

The boxes may be of any suitable material, 45 as for instance, of sheet metal, thin board, paper card-board, wood-pulp in sheets, or other material having the requisite properties.

In the accompanying three sheets of drawings, Figure 1 is a plan view of a sheet as cut out for a one-quart box. Fig. 2 is a side view of the box formed from the above blank: 50 Fig. 3 shows it from another side with the covers closed down, and Fig. 4 shows it in perspective. Fig. 5 is a plan view of a blank

for a five-quart box in which sections for handles are provided, and Fig. 6 shows the blank folded into a box. Fig. 7 is a plan 55 view of a modified blank for a one-quart box in which handle-sections are at the ends of the binding strips and the cover section is single instead of double, and Fig. 8 shows in perspective the box folded from this blank. 60 These views except Fig. 5 are drawn to appear one-fourth scale in the customary lithographic reproduction. Fig. 5 is one-eighth scale. The smaller boxes are preferably made from sheets of about one-sixteenth of an inch in 65 thickness.

In Fig. 1 I have shown a sheet twelve inches by eighteen inches in size, which folds up into a box five inches square at the bottom and three inches high. The dotted lines show 70 where the sheet is to be bent, and where it is preferable to have perforations or creases to facilitate the folding. These latter should be made upon the side of the sheet that is to be bent inward. As I shall for convenience 75 of description designate the side of the sheet shown as the inside, all of the indentations except those on the lines *s-s* and on the binding strips are on the side shown, those on these lines being on the other side. The sheet 80 for this box blank is formed in the usual way by saws or cutting machines which cut and indent them as shown in Fig. 1 and above described.

The box is preferably formed from one of 85 the blanks at the point where it is to be used and the operation is as follows: First, turn up the opposite side sections *B B* by bending the sheet along the dotted lines *b-b*, thus forming two sides of the box; next fold the 90 strips *A A* under, by bending the sheet along the dotted lines *s-s* so that they will lie against the under side of the sheet; next turn up the other side sections *C C* by bending along the dotted lines *c-c*, thus forming the 95 two remaining sides of the box; this brings the binding strip sections into the position in which they would be if folded outwardly and back upon the side sections after these side sections were turned up; next bend inward the corner sections *D D* and lap them together at the lapels *d d* back of the sides *B B*; next bring the ends *K K* of the strips *A A* around bending on the lines *k-k* and slip

each end K under the fold of the other strip; finally bring around the other ends G G after bending on the lines $g-g$ and lock them with the hoop locks provided at $a a$, tucking each 5 end G under the fold of the other strip. In order to secure the proper hoop lock and have the ends G G K K properly protected it is necessary that the notches $a a$ should be reversed in position relatively to each other as 10 shown, two of the notches being turned in toward the body of the blank, and the other two notches being turned outward. In other words the binding strips A A each consists of a middle section bounded by the lines $g-g$, 15 $k-k$, and $s-s$, which is an elongation of one of the side sections C and two lateral projection from this section in one of which is a notch a on the outer edge and turned away from the body of the blank and in the other 20 of which is a similar notch on the edge next to the body of the blank. The box is now completed but not closed as shown in Fig. 2.

After filling the box, the cover sections E E are folded inward at the line $e-e$, and 25 the side-fold sections F F are bent down at the lines $f-f$. The covers come together at the slit m and lapel l , and the side-fold sections are thrust into and supported in the slits $t t$. They thus form a bridge protecting 30 the fruit inside and capable of sustaining the weight of at least four filled boxes of the same size when piled on each other for shipment in a crate without intervening shelving. There is thus formed from one piece of material, without the aid of metal or other similar fastening, a box of one-quart capacity, securely locked together with a cover to protect the contents and serve as a support for other boxes. This sized box is particularly 35 designed for small fruits such as berries, plums and cherries, but I do not confine myself to the size shown.

It will be apparent that if the sections of the blank shown in Fig. 1 and there marked 40 with the letters D E and F, in all ten sections, be omitted a box can be formed which will have four sides, a bottom, and interlocking binding strips encircling the top of the box by which it is strengthened. These strips 45 will have their ends protected by each other's middle section. Such a box, although it would be useful, will not be as complete as one that is provided with covers made from the sections E E which are supported by the side-fold sections F F. The corner sections D D are useful additions in that they protect the corners and further strengthen the box. It 50 will be seen therefore that each one of the features which are added by making use of the sections D E and F are valuable though not essential features. The side fold sections F F which engage in the slits $t t$ may for some uses give sufficient strength to the box and render the binding strips unnecessary. It 55 will be seen that the whole blank is so planned that there is no waste material except the small notches cut out at the points $a a a a$.

These boxes are intended when filled to be packed by stacking them up one on top of the other within a crate of the form shown 70 and described in my pending application for an improvement in knockdown crates filed of even date herewith.

Figs. 5 and 6 show respectively a blank drawn to one-eighth scale and a five-quart 75 box made therefrom which is drawn to double the scale of the blank. In this modification sections H H to form handles inwardly project into the blank from the binding-strip sections, and two of the corner sections 80 D' D' are attached to the side sections B B, instead of to the sections C C as in the first described form. A double hoop lock is shown for the binding strips, and the notches are straight slits in this form as 85 shown. These changes obviate the necessity of having the binding strips long enough to turn the corners and to be tucked under the folds. A saving of at least two inches is thus 90 effected in the length of the blank and its folding into a box is facilitated. In folding this style of box the corner sections are preferably folded inside instead of outside the side sections, with the sections D D against the sides B B and the sections D' D' against 95 the sides C C. When the covers are closed down the side-fold sections are tucked next to the insides of the side sections C C and between them and the corner sections D' D'. These changes do away with the necessity for 100 slits in the sides and in the corner sections, and as all the sections D D' and F are thus folded inside of the box the outside, bottom and sides are left even and free from cuts, and the box is more easily formed, is stronger 105 and is more pleasing in its appearance. During shipment and while the boxes are packed in the crate the sections H H are bent over and lie flat on top of the covers, but are formed into handles by hooking them together at $h h$ for the purchaser to carry. 110

Figs. 7 and 8 show a blank and a one-quart box made therefrom. In this modification the side sections are turned up and the binding strips are turned under as before. The 115 corner sections are preferably turned inside the box. The ends K K' are next brought around, bending on the lines $k-k$. The notch a near the end K of the short strip is locked into a slit in one of the sides B, and the handle-section H at the end K' of the long strip is tucked through the slit S on the opposite side. The ends G G' are similarly brought around and secured. 120

Without limiting myself with the precise 125 details shown, what I claim, and desire to secure by Letters Patent of the United States, is—

1. A folding-box blank composed of a bottom section, sections which fold up to form 130 the sides, sections which fold back upon side sections outwardly to form binding strips, said binding strips being projections from side sections, the blank being suitably cut

and creased between the sections to effect the folds, substantially as described.

2. A folding-box blank composed of a bottom section, sections which fold up to form the sides, sections which fold back upon side sections outwardly to form binding strips, sections comprising the remaining portions of the blank to form the corners, the blank being suitably cut and creased between the sections to effect the folds, substantially as described.

3. A folding-box blank composed of a bottom section, four sections which fold up to form the sides, a top section which is an elongation of one of the side sections and folds over to form a cover, side-fold sections which are lateral projections of the top section and fold downwardly to support the top, slits in the side sections in which the side-fold sections are intended to rest, the blank being suitably cut and creased between the sections to effect the folds, substantially as described.

4. A folding-box blank composed of a bottom section, four sections which fold up to form the sides, a top section which is an elongation of one of the side sections and folds over to form a cover, side-fold sections which are lateral projections of the top section and fold downwardly to support the top, sections comprising the remaining portions of the blank to form the corners, the blank being suitably cut and creased between the sections to effect the folds, substantially as described.

5. A folding-box blank composed of a bottom section, four sections which fold up to form the sides, sections which fold outwardly to form binding strips, a top section which is an elongation of one of the side sections and folds over to form a cover, side-fold sections which are lateral projections of the top section and fold downwardly to support the top, the blank being suitably cut and creased between the sections to effect the folds, substantially as described.

6. A folding-box blank composed of a bottom section, sections which fold up to form the sides, sections which fold outwardly to form binding strips, said binding strips being projections from the side sections, handles which inwardly project from said binding-strip sections, the blank being suitably cut and creased between the sections to effect the folds, substantially as described.

7. A folding-box blank composed of a bottom section, sections which fold up to form the sides, sections which fold outwardly to form binding strips, handles which inwardly project from said binding-strip sections, sections comprising the remaining portions of the blank to form the corners, the blank being suitably cut and creased between the sections to effect the folds, substantially as described.

8. A folding-box blank composed of a bottom section, four sections which fold up to form the sides, sections which fold outwardly

to form binding strips, handles which inwardly project from said binding-strip sections, a top section which is an elongation of one of the side sections and folds over to form a cover, side-fold sections which are lateral projections of the top section and fold downwardly to support the top, the blank being suitably cut and creased between the sections to effect the folds, substantially as described.

9. A folding-box blank composed of a bottom section, four sections which fold up to form the sides, sections which fold outwardly to form binding strips, said binding strips being projections from side sections, handles which inwardly project from said binding-strip sections, two top sections which are elongations of two of the side sections and fold over to form covers, side-fold sections which are lateral projections of the top sections and fold downwardly to support the top sections, the blank being suitably cut and creased between the sections to effect the folds, substantially as described.

10. A folding-box made up from a blank composed of a bottom section, sections which fold up to form the sides, sections which fold back upon side sections outwardly to form binding strips, said binding strips being projections from side sections, the blank being suitably cut and creased between the sections to effect the folds, substantially as described.

11. A folding-box made up from a blank composed of a bottom section, sections which fold up to form the sides, sections which fold back upon side sections outwardly to form binding strips, sections comprising the remaining portions of the blank to form the corners, the blank being suitably cut and creased between the sections to effect the folds, substantially as described.

12. A folding-box made up from a blank composed of a bottom section, four sections which fold up to form the sides, a top section which is an elongation of one of the side sections and folds over to form a cover, side-fold sections which are lateral projections of the top sections and fold downwardly to support the top, slits in the side sections in which the side-fold sections are intended to rest, the blank being suitably cut and creased between the sections to effect the folds, substantially as described.

13. A folding-box made up from a blank composed of a bottom section, four sections which fold up to form the sides, a top section which is an elongation of one of the side sections and folds over to form a cover, side-fold sections which are lateral projections of the top section and fold downwardly to support the top, sections comprising the remaining portions of the blank to form the covers, the blank being suitably cut and creased between the sections to effect the folds, substantially as described.

14. A folding-box made up from a blank composed of a bottom section, four sections which fold up to form the sides, sections

which fold outwardly to form binding strips, a top section which is an elongation of one of the side sections and folds over to form a cover, side-fold sections which are lateral projections of the top section and fold downwardly to support the top, the blank being suitably cut and creased between the sections to effect the folds, substantially as described.

15. A folding-box made up from a blank composed of a bottom section which folds up to form the sides, sections which fold outwardly to form binding strips, said binding strips being projections from the side sections, handles which inwardly project from said binding-strip sections, the blank being suitably cut and creased between the sections to effect the folds, substantially as described.

16. A folding-box made up from a blank composed of a bottom section, sections which fold up to form the sides, sections which fold outwardly to form binding strips, handles which inwardly project from said binding-strip sections, sections comprising the remaining portions of the blank to form the corners, the blank being suitably cut and creased between the sections to effect the folds, substantially as described.

17. A folding-box made up from a blank composed of a bottom section, four sections which fold up to form the sides, sections which

fold outwardly to form binding strips, handles which inwardly project from said binding-strip sections, a top section which is an elongation of one of the side sections and folds over to form a cover, side-fold sections which are lateral projections of the top section and fold downwardly to support the top, the blank being suitably cut and creased between the sections to effect the folds, substantially as described.

18. A folding-box made up from a blank composed of a bottom section, four sections which fold over to form the sides, sections which fold outwardly to form binding strips, said binding strips being projections from side sections, handles which inwardly project from said binding strip sections, two top sections which are elongations of two of the side sections and fold over to form covers, side fold sections which are lateral projections of the top sections and fold downwardly to support the top sections, the blank being suitably cut and creased between the sections to effect the folds, substantially as described.

Signed by me this 23d day of November, 55
1893.

STEPHEN F. SHERMAN.

In presence of—

ANDREW J. LYNCH,
LOUIS SMIES.
